UNITED STATES PATENT OFFICE.

ANNA M. COLEMAN, OF PHILADELPHIA, PENNSYLVANIA.

BUST-FORM.

SPECIFICATION forming part of Letters Patent No. 745,787, dated December 1, 1903.

Application filed December 2, 1901. Serial No. 84,353. (No model.)

To all whom it may concern:

Be it known that I, ANNA M. COLEMAN, a resident of Philadelphia, in the county of Philadelphia and State of Pennsylvania, have 5 invented a Bust-Form, of which the following is a specification.

This invention is an improvement in bust-forms; and the object of the invention is to provide a bust-form which is light in construction, can be readily and conveniently adjusted to give the desired form, will provide for proper ventilation, and will generally improve the shape of the bust without discomfort to the wearer.

15 The primary object of the invention is to provide a bust-form which is extremely simple and cheap in construction and in which the fabric covering is easily detached, so that it may be regularly laundered.

20 The following specification enters into a detail description of my invention, reference being had to the accompanying drawings, and to letters of reference thereon which designate the different parts; and what I claim as 25 new in the particular construction of the bust-form and arrangement of parts constituting the same is more specifically set forth in the appended claims.

In the drawings which form a part of this 30 specification, Figure 1 is a view showing the application of my invention. Fig. 2 is a detail view of the bust-form, the fabric covering being removed. Fig. 3 is an end view. Fig. 4 is a sectional view.

35 In carrying out my invention I make the bust-form of two skeleton frames which are yielding and adjustably connected to each other, so that they may be applied to give the desired shape to the bust, and as these frames 40 A and A' are alike a description of one will also apply to the other, similar letters being used to indicate like parts in each frame.

The frame consists of the longitudinal ribs a and a connecting-stay a', attached centrally 45 to the aforesaid ribs. These ribs and the stay are made up of rust-proof bone-wire of very light weight and flexible and are incased in cotton, silk, or other fabric. In making up this frame the ribs a are curved outward 50 their entire length and their ends brought closely together and connected by a fabric covering b. The ribs are separated centrally

and held in proper relation to each other by means of the stay-wires a', and in making up the frame the central rib and stay are each 55 preferably composed of two bone-wires.

The complete bust-form consists of the two frames A and A', constructed as hereinbefore described, and said frames are connected by a safety-pin C, which permits them to be adjusted to and from each other.

Over the bust-form or frames A and A' is applied a fabric covering E, which may be gathered and trimmed to suit the fancy, and this covering is pinned to the ends of the 65 bust-form, as shown, and drawn tightly over the frames by the draw-strings e. By drawing upon these strings the shape of the bust can be changed, so that the desired shape of figure can be had. The device is secured in 70 place by pinning it to the corset or to the corset-waist or other garment, and being light in construction and yielding will remain in place and give a light natural form to the bust.

In use the device presents a perfectly-natural form by allowing the oblong shape to extend to the armpits, giving the fullness on the sides, which appears when the natural form is well rounded and readily yielding to 80 conform to the movements of the body. The device also provides for ventilation by permitting a free circulation of air, and by having the covering detachable it can be laundered and kept perfectly clean.

Having thus described my invention, what I claim as new, and desire to secure by Letters Patent, is—

1. A bust-form, comprising the skeleton frames each consisting of longitudinal ribs a connected together intimately at their ends and curved outward and separated intermittently, as shown, a transverse stay or rib a' extending across the under side of the ribs a and attached thereto to hold the latter in 90 proper position with relation to each other, and the tabs b projecting from the ends of the frame and providing the means by which the two frames are connected together in forming the bust-form.

2. A bust-form, comprising the skeleton frames each consisting of longitudinal ribs a connected together intimately at their ends by fabric strips and curved outward and sep-

arated intermediately, as shown, a transverse stay or rib a' extending across the under side of the ribs a and attached thereto to hold the latter in proper position with relation to each other, tabs b at the ends of the frame formed by extending the aforesaid fabric strips, and means for connecting the tabs in making up the bust-form and whereby the frames may be reversed; together with the fabric cover-

ing attached to the tabs at the outer ends of 10 the bust-form and provided with draw-strings.

In testimony whereof I affix my signature in the presence of two witnesses.

ANNA M. COLEMAN.
